To all whom it may concern:

Be it known that I, HENRY HORAN, of East Orange, in the county of Essex and State of New Jersey, have invented a new and original 5 Design for Carpets, of which the following is a specification.

C is a representation of a water-lily in appropriate leaves. It also is contained in figure D, which is nearly octagonal.

E is a geometrical figure placed diagonally between the figures C and D, as shown. It forms series of obliquely-placed squares and rectangles.

3. The design for carpets, consisting of the figures A B C D, substantially as shown.
